UNITED STATES PATENT OFFICE.

KIRKE W. CONNOR, OF DETROIT, MICHIGAN.

METHOD AND APPARATUS FOR MIXING COLORS.

1,403,485.

Specification of Letters Patent. Patented Jan. 17, 1922.

Application filed October 10, 1919. Serial No. 329,659.

To all whom it may concern:

Be it known that I, KIRKE W. CONNOR, a citizen of the United States of America, residing at Detroit, in the county of Wayne 5 and State of Michigan, have invented certain new and useful Improvements in Methods and Apparatus for Mixing Colors, of which the following is a specification, reference being had therein to the accompanying drawings.

The invention relates to the art of mixing colors or pigments and the invention consists in certain improved features as hereinafter set forth.

In the present state of the art liquid paints are usually formed by the grinding of the pigments in the oil, or other liquid, to produce a fine suspension. Fine grinding is best accomplished by a stone mill, but it 15 has been found desirable to perform a preliminary coarse grinding by a metal mill, more particularly for the purpose of providing a uniform feed for the stone mill. It is also necessary to first mix the dry pigments with the liquid and this operation is usually performed at a point more or less remote from the grinding mills. Therefore, as usually carried out, the complete process includes; first, the step of introducing the 20 dry pigments in proper proportion into the liquid; second, the thorough mixing of these ingredients with the liquid, usually performed in a rotary agitator; third, the transfer of the mixing to the grinding mills; 25 fourth, the coarse grinding; and; fifth, the fine grinding.

In the several transfers of the material from one part of the apparatus to another a considerable quantity of paint will adhere 30 to the sides of the receptacle. This necessitates labor of cleaning the receptacles and also involves waste of materials. It is not feasible to perform the mixing at the grinding mill and as the preliminary mixing is 35 performed in the rotary agitator at the point of compounding, a separate vessel is required for its transfer to the hopper of the grinder.

To simplify the process and eliminate 40 waste, I dispense with the separate transfer vessel and perform the mixing in a portable vessel which is first stationed at the point of compounding and after the mixing operation carried to the grinders. Furthermore, 45 to maintain a good mixture and to prevent the material from falling out of suspension 50

before entering the grinders, provision is made for continuing the agitation of the mixture in the portable container until the contents are entirely discharged into the 55 grinder. This is accomplished by a construction of portable mixer, including an agitator therein and means by which said agitator may be driven both at the original point and while in proximity to the grinder. 60 My improvement therefore comprises a method and an apparatus, illustrated in the drawings, in which—

Figure 1 is a vertical central section 70 through the mixing tank;

Figure 2 is an elevation of the grinder showing the portable mixer in operative relation thereto;

Figure 3 is a plan view of Figure 2.

A is a portable mixer which, as shown, is 75 in the form of a cylindrical tank having a bottom B preferably raised above the lower edge of the side walls. C is a rotary agitator within the tank consisting of radial arms C' and obliquely arranged blades or 80 paddles C². This agitator is driven from a shaft D, which preferably extends upward through the bottom B of the tank and through a central tube E extending upward above the level of the liquid therein. The 85 upper end of the shaft is connected with a tubular member F surrounding the tube E and attached at its lower end to the radial arms C'.

For effecting the preliminary mixing the 90 portable mixer A is placed upon a machine, including a rotary table G mounted on a frame H and driven through the medium of the beveled gear wheels I and J from a drive shaft K. This machine is also provided 95 with the means for driving the agitator C in a reverse direction to the rotation of the table G, this comprising a beveled gear wheel I. A shaft M on which the gear wheel L is mounted, passing axially through the gear 100 wheel I and rotary table G, has a coupling clutch N for rotatively attaching the shaft M with the shaft D. The arrangement is such that when the portable mixer A is in engagement with this machine, the outer 105 tank will be revolved in one direction and the agitator paddles in the opposite direction, thereby effecting a thorough mixing and commingling of the dry pigments with the liquids.

The grinder is of a construction heretofore used, comprising a stone mill O and a 110

metal mill P arranged thereabove. There is also a hopper or receptacle Q into which the mixture is placed to be fed successively to the grinders P and O. The grinders are 5 axially aligned and are driven from a shaft F, which in turn is driven through the medium of beveled gear wheels S and S' from the drive shaft T.

As previously described it is the usual

- 10 process to transfer the mixture from the mixing machine into the hopper Q. With my improvement the portable mixer A is removed from the table G, is carried to the grinder and is placed on a stationary table U adjacent to the mill P and above the level of the same. The grinder is also provided with a shaft V passing through the table U and having a coupling engagement with the shaft D, while the shaft V is driven through 20 the medium of the gear wheels W and W' from the shaft R. With the arrangement just described as soon as the materials have been sufficiently mixed in the machine shown in Figure 1, the tank A is removed and 25 placed on the table U where the agitation will be continued by the driving of the agitator C from the shaft V. The outer wall of the tank A is provided near its lower end with a valve X which may be 30 intermittently opened to fill the mill P with the mixture.

- In the manufacture of certain grades of colors it is necessary to regrind the material after it is once passed through the mill. 35 With my improvement this may be accomplished by collecting the ground material discharged from the mill in a portable mixer, such as above described, and in then placing this mixer upon the table U and feeding 40 the contents again into the hopper Q. Thus

the same vessels are used for the original mixing for feeding the mixed material into the grinder and for collecting from the grinder and feeding material a second time therethrough.

45

What I claim as my invention is:

1. The process of preparing plastic paints comprising compounding the liquid and dry ingredients at a given point and in a portable mixer, mixing the materials therein 50 at said point, transporting said portable mixer with the mixed materials therein to a grinder located at a remote point, mounting said mixer in operative relation to said grinder and simultaneously mixing, feeding 55 and grinding.

2. The process of preparing plastic paints comprising compounding the liquid and dry ingredients in a portable mixer, mixing the materials therein at the point of compounding, transporting the mixer and its content to a grinding mill located at a remote point, mounting said mixer in operative relation 60 to said mill to continue the agitation of the mixer during the grinding of the mill, and 65 means for feeding the material from said mixer to the grinder.

3. In a paint producing apparatus, the combination with the grinding mill, of a portable container for the compounding of 70 ingredients, an agitator therein, means located at a point remote from said mill for operating said agitator, and means for mounting said portable container in operative relation to said mill to continue the 75 agitation while feeding the material to the grinder.

In testimony whereof I affix my signature.

KIRKE W. CONNOR.
